UNITED STATES PATENT OFFICE.

ARTHUR J. SKINNER, OF SPRINGFIELD, MASSACHUSETTS, ASSIGNOR TO ORLAND V. SMITH, OF MILFORD, CONNECTICUT.

DEPOSIT-BOOK.

1,196,743.

Specification of Letters Patent. Patented Aug. 29, 1916.

Application filed December 21, 1915. Serial No. 68,002.

To all whom it may concern:

Be it known that I, ARTHUR J. SKINNER, a citizen of the United States of America, residing at Springfield, in the county of 5 Hampden and State of Massachusetts, have invented a new and useful Deposit-Book, of which the following is a specification.

My invention relates to improvements in deposit books for use jointly by banking institutions and their customers or depositors in connection with special accounts, such as so-called "Christmas accounts" and the like, and said invention resides in a book made up of one or more permanent or master 10 leaves or pages having one or more rows of characters arranged thereon, preferably adjacent to one edge thereof, and a plurality of serially numbered detachable or deposit leaves or pages or coupons having one or 15 more rows of characters arranged thereon to coincide with corresponding or appropriate characters on the master page above or in front, so that any corresponding, appropriate, or agreeing characters on said 20 master page and the deposit page immediately under or in front of the same can readily be punched at a single operation, there also being a certain agreement between the 25 master page characters and the coupon characters and serial numbers, all as hereinafter set forth.

This book may and preferably will be provided with a suitable table setting forth certain data that is useful in connection with 30 the master page or pages and the deposit pages or coupons.

The principal object of my invention is to produce a simple and inexpensive book, by means of which the special bank account 35 can, with the minimum amount of time, trouble and labor, be accurately kept, so that both the bank and the customer or depositor may at all times know the amounts which have been deposited and which are required 40 to be deposited, both parties to the contract always having in their possession a complete record of each and every transaction involved from the time the contract begins to run until it is terminated.

50 A further object is to provide a book of this type with which can be used to advan-

tage a table of related or pertinent data if desired.

This book is compact and convenient, requires no signatures, and is withal highly 55 practicable and efficient.

Other objects and advantages will appear in the course of the following description.

Although I have embodied my invention in a Christmas deposit book, for illustrative purposes in connection with this application, said invention is not limited to deposit books used for Christmas accounts.

I attain the objects and secure the advantages of my invention by the means illustrated in the accompanying drawings, in which—

Figure 1 is a perspective view of a deposit book which embodies a practical form of my invention, the front cover being open 70 to expose the table on the inside thereof and the first permanent or master leaf or page, of which there are two in the present case; Fig. 2, a similar view, but with said master page turned over and the first detachable 75 leaf or page, or the first coupon, exposed, and; Fig. 3, a view similar to the second, except that the book is open to the other master page.

Similar reference numerals designate similar parts throughout the several views.

The book of the drawings comprises a front cover 1, two master pages 2 and 3, and a series of fifty coupons 4, thirty of such coupons being between the two master pages 85 and the other twenty following the master page 3.

On the inside of the cover 1 is printed a table which is divided vertically by suitable rulings into two divisions and these into four 90 subdivisions, and made up as follows: In the left hand column of each division are the coupon numbers arranged consecutively front top to bottom; in the next column are the payment dates similarly arranged, 95 commencing with December 27, 1915, and ending with December 4, 1916, in the second section at the bottom; in the next column are the amounts of the weekly payments, and in the last column are the monthly 100 amounts, the total in this case being \$100 which appears at the bottom of the monthly

column in the second division. Appropriate headings are printed above the columns of the table to indicate exactly what the matter below represents or stands for. This table 5 is clearly shown in Fig. 1.

The master page 2 has printed thereon consecutively, in three rows of spaces formed by rulings, the numerals from 1 to 30, with a reference above to the table. These numerals represent the first thirty payments, and one of them is to be punched at the bank each time a payment is made, together with the coupon 4 immediately below or following, as will presently be more fully 10 explained. This numeral table is located near the bottom of the page so that each numeral therein will be accessible to the punch and the space containing such numeral can be conveniently perforated there- 15 with.

The master page 3 has printed thereon, consecutively in two rows of spaces formed by rulings, the numerals from 31 to 50, such rows being arranged in the same relative 20 position on said page as are those in the second and third rows on the first master page. The numerals on the master page 3 represent the last twenty payments, and one of them is to be punched at the bank each 25 time a payment is made, together with the coupon immediately below.

A single master page might be employed by enlarging the table on the master page 2 to include the table on the master page 3, 30 but for the sake of economy in the manufacture of the book and convenience in punching I prefer to provide a master page for the numerals in excess of 30 or any multiple thereof.

40 Directions or other matter may be printed in the spaces above the tables on the master pages 2 and 3.

The coupons 4 are longer than the master pages 2 and 3, so that the former project 45 at their free ends beyond the latter, and the projecting end portions of said coupons are grasped when the coupons are detached. Thus provision is made for convenient detachment of the coupons, and liability of 50 tearing out the master pages with the coupons is eliminated.

Each coupon 4 is scored or partially cut, as represented at 5 in Fig. 2, to weaken the same along a line which extends crosswise 55 of said coupon near the bound end thereof, which weakened line divides the major portion of the coupon from the binding portion, and renders such major portion readily detachable.

60 A table comprising rulings and numerals is printed on the lower part of each coupon 4, in agreement locally with the table on the master page 2, there being three rows of numerals as on said page, and each of such numerals being under or behind a corre-

sponding numeral on said page, so that corresponding numerals on the master page and the coupon immediately following can be punched at the same time, when the book is open and the two members are held together and separated or raised from the other members for the insertion and application of the punch. The foregoing applies also to the master page 3 and the coupons 4 which follow the same, but the middle and 70 bottom rows of numerals on these coupons are the only ones used, because there are but two rows of numerals on said page. The reason that the top rows of numerals are retained in the case of the coupons which 75 follow the master page 3 is because it is cheaper to print all of the coupons alike, otherwise such rows could be omitted. Also, on account of cheapness, I prefer to employ in sequence the nine digits and the cipher 80 85 in each row on each coupon, instead of progressive numerals like those on the master pages 2 and 3. The digits and ciphers serve to impart clearly to the bank the desired information, and to present the same in permanent record form, each transaction being accurately denoted by a punched digit or cipher, while at the same time this part of the record may be obscure to the depositor. But the depositor has his permanent record 90 95 in the punched master page or pages and need not be concerned about the details of the bank record. All of this will presently be more fully explained.

Each coupon 4 preferably has printed 100 thereon above the table an account number, as "Account No. 11019," the amount to be paid into the bank each week, as "\$2.00," and the serial number, as "Coupon No. 1," the serial numbers running consecutively 105 from 1 on the first coupon, as shown in Fig. 2, to 50 on the last coupon. The aforesaid weekly amount and the serial numbers correspond to like notations in the table on the front cover 1.

110 In practice, when the first payment is made, the numeral 1 on the master page 2 and the coupon 4 which immediately follows said page are punched, and said coupon is removed and filed at the bank. The 115 depositor now has a punched record of his first deposit, in the master page 2, and the bank also has a punched record of the same, in the No. 1 coupon punched in the first space. The punching and detaching operations are repeated, as the subsequent deposits are made, until the total amount is paid in and the last coupon detached. At the tenth payment the numeral 10 on the master page 2 and the top cipher on coupon 120 125 No. 10 are punched, at the eleventh payment the numeral 11 on said page and the middle digit 1 on coupon No. 11 are punched, and so on until at the last payment the numeral 50 on the master page 3 and the 130

bottom cipher on coupon No. 50 are punched, in each case the punched master-page numeral plainly showing to the depositor the number of the payment, and the punched numeral on the coupon corresponding with the serial number of said coupon and with the corresponding numeral on one or the other master page constituting a record for the bank of the transaction. The 10 records balance and either proves the other.

It will be understood that, as the top cipher on coupon No. 10 stands for that numeral and the middle digit 1 on coupon No. 11 stands for that numeral, each of the following digits in the middle row of the table on any of the coupons 4, which precede the master page 3, is to be read with the figure 1 before it, and the cipher in such row with the figure 2 before it, and that each of the 20 digits in the bottom row of said table is to be read with the figure 2 before it, and the cipher in said last mentioned row with the figure 3 before it, 30 being the serial number of the coupon just before the master page 3; and that each of the digits in the middle row of the table on any coupon, which follows said master page 3, is to be read with the figure 3 before it, and the cipher in the same row with the figure 4 before it, and that each of the digits in the bottom row of said table is to be read with the figure 4 before it, and the last cipher as 50 as before stated. The punched digit or cipher on a coupon must agree with the 30 serial number of such coupon, otherwise there is conclusive evidence of an error. As an example of this, let it be assumed that coupon No. 26 is punched in the bottom 5 space. It is seen at once that the coupon is 40 incorrectly punched, and search will be instituted to ascertain the cause of the error. There must be perfect agreement and exact accord between the master page and coupon punchings and the coupon serial numbers, or else there is present unmistakable 45 evidence of error.

Should the depositor desire to deposit more than the required amount at a given time, as for a month in advance, for illustration, he can determine the exact sum required by referring to the table on the cover 1, and can see, when after depositing such

sum and the book is handed back by the bank official, that the master page or pages have been correctly punched and the proper 55 number of coupons detached.

Although the table on the front cover is of considerable advantage, especially in a book intended for the purpose of that which I have herein shown and described, 60 such table might be omitted. The book, if designed for use in some other field, will probably require a different table, or may not need any at all, and may call for more or less change in the matter printed on the 65 master pages and coupons, but any omission or change, such as is here contemplated, will not be of a nature to affect the essence of my invention. In this connection it is to be noted that the location may be changed 70 on the cover table.

It is quite evident that other characters might be used, in connection with my book, besides numerals or the digits, ciphers, numbers, and figures commonly classed as numerals, hence the term character or characters, as herein employed, is not intended to be limited to numerals.

What I claim as my invention, and desire to secure by Letters Patent, is— 80

1. A deposit book, of the class described, comprising one or more master pages having sequentially arranged thereon numerals to be punched, and detachable numbered coupons backing such page or pages, the 85 number of such coupons being equal to the highest numeral on such page or on each of such pages, and said coupons having thereon characters of progressive values to be punched, said numerals and said characters being in registration when the sheets are superposed.

2. A deposit book, of the class described, comprising one or more permanent pages having thereon characters to be punched, and a plurality of numbered detachable leaves backing said page or pages and having thereon characters to be punched, the characters on said page or pages and said leaves being in registration when the sheets are superposed, and said leaves projecting at one end beyond said page or pages. 95 100

ARTHUR J. SKINNER.
